CLAIM

The ornamental design for a screwdriver, as shown and
described.

DESCRIPTION

FIG. 1 is a side elevational view of a screwdriver showing
a first embodiment of our new design, the top, bottom
and opposite side being identical;

FIG. 2 is an end elevational view thereof;

FIG. 3 is an opposite end elevational view thereof;
FIG. 4 is a side elevational view of a screwdriver showing
a second embodiment of our new design, the top,
bottom and opposite side being identical;

FIG. 5 is a side elevational view of a screwdriver showing
a third embodiment of our new design, the top,
bottom and opposite side being identical;

FIG. 6 is a side elevational view of a screwdriver showing
a fourth embodiment of our new design, the top,
bottom and opposite side being identical;

FIG. 7 is a side elevational view of a screwdriver showing
a fifth embodiment of our new design, the top,
bottom and opposite side being identical;

The end views of the embodiments depicted in FIGS.
4-7 are identical to those shown in FIGS. 2 and 3.

FIG. 8 is a perspective view of the screwdriver of
FIGS. 1-3; and

FIG. 9 is a side elevational view of the screwdriver of
FIGS. 1-3 similar to FIG. 1 except that it has been
rotated 45°.

FIG. 1

FIG. 2

FIG. 3

FIG. 4

FIG. 5

FIG. 6

FIG. 7
